AUTOMOBILE DOOR HINGE

Seth B. Atwood, Rockford, Ill.

Application October 30, 1937, Serial No. 171,825

3 Claims. (CL 296—44)

This invention relates to automobiles, and is particularly concerned with improvements in the door hinges.

The latest trends in automobile body design have presented serious problems in the hinging of the doors. Automobile bodies are being given outside curvatures for pleasing appearance and increased roominess within, entirely without regard to how this change in shape is to be taken care of in the matter of hinging the doors. Usually with these designs there is considerable "turn-under" on the sides, that is, the belt line or mid-portion stands out appreciably from the lower portion. In such designs, if exposed pintle type hinges were used, the lower hinges would have to project to such an extent that one could not possibly use pintle hinges for the top and bottom hinges of the door. On the other hand, the amount of door throw required to bring the edge of the door clear of the bulged exterior of the body is such that there wouldn't be room in the door pillar to accommodate the size of gooseneck members that would be required if concealed hinges were to be used at the top and bottom of the door. It is therefore the principal object of my invention to provide as a practical compromise design a combination of one pintle hinge projecting slightly from the body and one ball-and-socket hinge concealed within the body, the pintle axis being on a line through the center of the ball and socket of the other hinge, whereby to obtain the desired throw without any substantial or objectionable showing of hinges on the outside of the body, the short stubs projecting at the lower hinge locations being hardly noticeable, and by reason of their lower location, being not at all objectionable.

The invention is illustrated in the accompanying drawing, in which—

Figure 1 is a side view of a portion of an automobile body, the door of which is shown equipped with hinges in accordance with my invention;

Fig. 2 is a transverse vertical section through the body showing the door open and also showing the relationship of the hinging axis to the bulge of the body, and

Fig. 3 is a horizontal section through the concealed ball-and-socket hinge.

The same reference numerals are applied to corresponding parts throughout the views.

The body 4 and door 5 provided for the door opening 6 in the body have corresponding convex curvature on the exterior thereof, there being a pronounced bulge in the vicinity of the mid-portion or belt line 7 with a proportionate in-

ward curvature or turn-under in the lower portion 8, in keeping with the present body styling. Such shapes, unless referred to as streamlined, are designed both for pleasing appearance and increased passenger space inside the body. This curvature obviously requires increased door throw to bring the curved edge of the door clear of the curved outside of the body when the door is opened. Now, obviously, if one were to use two pintle hinges for the top and bottom of the door, the hinges would have to project so far from the outside of the body that they would seriously detract from the appearance of the car and be totally out of harmony with the streamline design. On the other hand, the amount of door throw required is such that one cannot use concealed hinges because the pillars are not large enough in cross-section to afford space therein for the size of gooseneck members that would be required. In accordance with my invention, I obtain the desired location of the door hinging axis $x-y$, shown in Figs. 1 and 2, by providing a concealed ball-and-socket hinge 9 for the upper hinge and a short stub form of exposed pintle hinge 10 for the lower hinge. The pintle 11 of hinge 10 is on the axis $x-y$ and the axis coincides with the center of the ball 12 in the socket 13 of the hinge 9. This fact is further illustrated in Fig. 3 in which the hinge 10 appears in dotted lines beneath the hinge 9 with the pintle 11 and ball 12 in vertical alignment on the axis $x-y$. With this combination of hinges, the axis $x-y$ is located partly within and partly outside the body 4, as clearly appears in Fig. 2, and I am enabled to use a concealed type hinge 9, the gooseneck member 14 of which is not too large to fit nicely within the confines of the pillar 15, and there is furthermore very little projection of the pintle hinge 10, so little in fact that it is hardly noticeable on the automobile, because of its lower location. Any attempt to use two concealed hinges would necessitate shifting the axis $x-y$ inwardly relative to the outside of the body to such an extent that if the axis could be brought entirely inside the pillar 15, the size of gooseneck members 14 required would make the construction impractical, because there wouldn't be room enough in the pillar to accommodate these members.

The hinge 9 is similar to that shown in my application Serial No. 135,068, filed April 5, 1937, and comprises the angular gooseneck member 14 with the ball head 12 on one end and having its other end knurled, as at 16, and arranged to be clamped by a plate 17 fastened to the door by 55

screws 18. The socket member 19 of the hinge 9 is made from two sheet metal stampings 20 and 21 of right-angle form suitably secured together to provide the socket 13 therebetween, half in the part 20 and the other half in the part 21 with registering slots extending from the socket 13 through which the gooseneck member 14 extends for swinging movement through about 90°. Bolts or screws 22 serve to fasten the socket member 13 to the door pillar 15. The construction of the socket member 19 is such that the gooseneck member 14 is free to swing through approximately 90° and, as appears in Fig. 2, the slot in socket member 19 is wide enough in relation to the diameter of the gooseneck shank to allow appreciable adjustment of the angular ball-carrying end of the gooseneck without interfering with the swinging of the door to and from closed position.

In mounting the door 5 the ball and socket hinge 9 and pintle hinge 10 are, of course, first attached to the door and pillar. Inasmuch as the pintle hinge 10 is not adjustable, save by bending, the ball and socket hinge 9 accommodates itself to its companion pintle hinge by the adjustability of the gooseneck member 14 which, as shown, is adjustable rotatably and endwise with respect to the clamping means 17-18 whereby to locate the ball head 12 in the socket without any cramping of the hinge assembly. This adjustability of the ball and socket hinge 9 will, of course, be taken advantage of to a certain extent also in centering the door at least so far as the upper half thereof is concerned. Then if it is found necessary to bend the pintle hinge 10 to properly position the lower part of the door, that can be done in the usual way, as by application of a forked tool to the projecting pintle carrying end of the hinge. Now, it is obvious that if the other hinge were a pintle hinge, bending of the hinge 10 would destroy the alignment of pintles and create a cramped condition, but with the present invention, because the ball and socket hinge 9 provides point suspension, there is no cramping because the ball head 12 merely adjusts itself in the socket 13 to accommodate the deviation one way or the other of the pintle axis due to bending. In other words, the hinging axis might be described as warped, but nevertheless the door swings much more freely than it would if two or more pintle hinges were employed, because the universally adjustable hinge 9 can so readily adapt itself to the adjustment of the pintle hinge by reason of the fact that it provides point suspension and the point referred to determines the upper end of the hinging axis.

While I have shown an automobile body with pronounced "turn-under" calling for the arrangement of hinges illustrated, it should, of course, be evident that a similar combination but with the hinges in the reverse relationship, that is, with the pintle hinge on top and the ball-and-socket hinge on the bottom, may be used on some bodies of other shape. However, most automobile bodies will conform to the present disclosure and use the arrangement of hinges as shown. Also, while the hinging axis $x-y$ is shown as substantially vertical, it may be inclined outwardly or inwardly slightly from a true vertical, the pintle 11 in any case being on the axis passing through the center of the ball and socket of the other hinge.

It is believed the foregoing description conveys a good understanding of the objects and advantages of my invention. The appended claims are drawn with a view to covering all legitimate modifications and adaptations.

I claim:

1. In an automobile construction, door and body portions having curved outside surfaces, said body portion including a hollow door pillar, a concealed type ball-and-socket hinge constituting one of a pair of hinges for hingedly mounting the door on the body, and a pintle hinge constituting the other of said pair, the former comprising a socket member mounted in the pillar, and a horizontal angular gooseneck member terminating at one end in a ball head swivelled in a socket provided in the socket member, the other end of the gooseneck member being an attaching end and having means for securing the same to the door for rotary and horizontal endwise adjustment thereof for vertical and horizontal adjustment of the ball head, the pintle hinge comprising hinge members fixed to the door pillar and door near the bottom thereof and pivotally connected by a pintle located outside the body on a hinging axis which passes through the center of the ball and socket of the first-mentioned hinge, the hinging axis being partly inside the body and partly outside the same.

2. In an automobile construction, door and body portions having curved outside surfaces, said body portion including a hollow door pillar, a concealed type ball-and-socket hinge constituting one of a pair of hinges for hingedly mounting the door on the body, and a pintle hinge constituting the other of said pair, the former comprising a socket member mounted in the pillar, and a horizontal angular gooseneck member terminating in a ball head swivelled in a socket provided in the socket member, the gooseneck member being adjustably secured to the door for horizontal and vertical adjustment of the ball head, the pintle hinge comprising hinge members fixed to the door pillar and door in vertically spaced relation to the first hinge and pivotally connected by a pintle located outside the body on a hinging axis which passes through the center of the ball and socket of the first-mentioned hinge, the hinging axis being partly inside the body and partly outside the same.

3. A pair of hinges for mounting a door on a vehicle body, one of said hinges being a pintle hinge comprising hinge members pivotally connected by a pintle and adapted to be secured to a door and body, and the other hinge comprising a socket member and a gooseneck member, one of which members is adapted to be secured to the door and the other to the body adjacent the door opening therein, the gooseneck member comprising a substantially horizontally disposed angular shank with a ball head on one end thereof operating in the socket of the socket member with a swivel action, the other end of the shank being the attaching end, and means for securing the attaching end of said shank to one of said door and body for rotary and horizontal endwise adjustment whereby to provide vertical and horizontal adjustments respectively of the ball head thereof.

SETH B. ATWOOD.
